ABSTRACT OF THE DISCLOSURE

Fluorinated organomercury compounds, useful in the construction of floated control instruments, have the formulae:

and

wherein R is selected from the group consisting of $-\text{CH}_3$, $-\text{CF}=\text{CF}_2$,

and

R_1 is selected from the group consisting of $-\text{CH}_3$, $-\text{CF}=\text{CF}_2$,

and

R_2 is selected from the group consisting of $-\text{CH}_3$, $-\text{CF}=\text{CF}_2$, and

and X is selected from the group consisting of chlorine, bromine, fluorine and $-\text{HgCH}_3$.

This invention relates to floated control instruments in which the flotation fluid is a fluorinated organomercury compound.

In a floated gyroscope the rotor is encased in a float suspended in a fluid, the density of which is chosen to correspond to that of the float. Such an arrangement makes

for exceedingly low pivot-friction since the float is supported almost completely by pressure gradients in the fluid. Moreover, the gyro fluid protects the assembly from shock, provides a damping function and serves as a heat transfer medium to dissipate heat developed by the rotor. Where the damping effect on the precession of the float is largely developed by the fluid itself a fluid is generally selected having a high viscosity. However, where damping is not desired or where electronic or orifice damping is employed low viscosity liquids are preferred.

10 In addition to the above described uses in a single gyroscope, a gyro fluid may be used in a system wherein one or more gyros and associated equipment are mounted on a platform which is floated in the fluid. For this application the fluid is usually a dense, low viscosity liquid.

15 The liquids which are useful in gyroscopes must have certain critical physical characteristics. High density is required—at least about 1.6 g./ml. The greater the density the more useful the fluid since this permits more inertia to be built into the rotor without imposing higher loads on the pivot. A higher density fluid allows size reduction at the same amount of inertia (and sensitivity of the gyro). A second requirement of such liquids is Newtonian behavior, i.e., the viscosity is independent of the shearing rate. Preferably, the liquid should be relatively insensitive 20 to viscosity to temperature variations. The latter property enables the fluid to remain useful over the operational temperature range of the gyroscope.

25 Finally, it is essential that the liquid exhibit chemical stability under the operating conditions of the gyroscope since any degradation or breakdown products would very likely cause corrosion of the gyroscope parts.

30 It is extremely difficult to find a fluid possessing the aforesaid requirements. Fluids in general use today 35 are based on fluorocarbons because of the known stabilizing effect of large numbers of fluorine atoms on halogenated carbon compounds. The high viscosity fluids are generally telomers of $\text{CFCl}=\text{CF}_2$ and of $\text{CFBr}=\text{CF}_2$ having densities in the range of about 1.7 g./ml. to about 40 2.4 g./ml., respectively. Where low viscosity liquids are required, low molecular weight ends of the telomerization product of the olefins are sometimes employed; a volatile fluorinated cycloether having the empirical $\text{C}_8\text{F}_{16}\text{O}$ and a density of 1.7602 g./ml. at 25° C. is also in common use. Halogenated hydrocarbons other than fluorinated hydrocarbons have proven to be more or less sensitive to hydrolysis and thermal decomposition thereby forming hydrohalic acids and/or free halogens which are 45 highly corrosive to certain metal parts in the gyroscope.

50 It has now been discovered that certain novel organomercury compounds having a substantial degree of fluorine substitution serve as excellent gyro fluids and the provision of the aforesaid compounds and their use as gyro fluids constitute the principal objects and purposes of the invention. Other objects and purposes will be made manifest subsequently.

55 The novel fluorinated organomercury compounds herein are disubstituted organic mercury compounds characterized in that at least one of the organic substituents is a lower cycloalkenyl group having a substantial degree of fluorination. The configuration of the compounds is more readily visualized by reference to the following formulae:

and

(III)

wherein R represents $-\text{CH}_3$, $-\text{CF}=\text{CF}_2$,

and

R_1 represents $-\text{CH}_3$, $-\text{CF}=\text{CF}_2$,

and

R_2 represents $-\text{CH}_3$, $-\text{CF}=\text{CF}_2$, and

and X represents chlorine, bromine, fluorine and $-\text{HgCH}_3$. R is preferably $-\text{CH}_3$ or $-\text{CF}=\text{CF}_2$.

The fluorinated disubstituted organomercury compounds of the invention can be realized by a series of chemical transformations starting with the appropriately substituted fluorinated cycloalkene having a bromine attached to a double bond carbon, and replacing the bromine, through a series of intermediate steps, with an organo-mercury residue to give the desired configuration. The sequence of reactions can be depicted more concisely by the following chemical equations:

where Z completes the fluorocycloalkene nuclei of Formulas I, II and III, M is an organometallic residue such as an alkyl lithium or $-\text{R}'\text{MgX}'$ where R' is lower alkyl and X' is chlorine, bromine or iodine and R_3 has the values R, R_1 and R_2 defined elsewhere herein except where R_3 contains a carbon-mercury bond such as

In these instances the R_3M is not formed from the organometallic reagent since the latter may cleave the mercury-carbon bond. Where R_3 contains $-\text{HgCH}_3$ such as

the methylmercuritetrafluorophenylcycloalkylmercury is prepared by an alternate route as illustrated by the following equations:

10

20
25

In general, the reactions are carried out by combining stoichiometric amounts of components in the presence of an inert, normally liquid organic solvent such as diethyl ether. It is preferable to conduct the reactions under an inert atmosphere such as dry nitrogen. The temperature should be less than room temperature, preferably about 0° C .

The requisite fluorinated 1-bromocycloalkene intermediates are obtained using a procedure patterned after that of J. D. Park et al., J. Org. Chem., 29, 3664 (1964). One of the intermediates, 1-bromo-2-chloro-3,4,4,5,5,5-hexafluorocyclopentene has not previously been synthesized.

The fluorinated organomercury compounds are unusual in that they possess high density—of the order of 2.7 g./ml.—while being remarkably stable. It is these dual properties which make them especially suitable for use as gyro fluids.

Reference is now made to the following non-limited examples.

40 Example 1.—2,3-dichloro-3,4,4-trifluoro-1-cyclobutenylmercury

45

(A) Preparation of 2,3-dichloro-3,4,4-trifluoro-1-cyclobutenylmercuric chloride.

Into a 250 ml., three neck flask previously flame dried and swept out with nitrogen and equipped with a thermometer, a pressure equilibrated addition funnel, a condenser with drying tube and a magnetic stirrer is charged 50 0.973 g. (0.04 mole) of magnesium (99.99% purity) and 10 ml. of dry ether. A solution of 4.5 g. (0.041 mole) of redistilled ethyl bromide in 30 ml. of dry ether is then added at such a rate as to sustain gentle refluxing of the flask contents. The reaction is refluxed 1½ hours longer after which a few drops of ethyl bromide is added to react with any residual magnesium. The resulting Grignard reagent is cooled to 0° C . and so maintained while 55 adding dropwise thereto a solution of 8.96 g. (0.035 mole) of 1-bromo-2,3-dichloro-3,4,4-trifluoro-1-cyclobutene in 80 ml. of dry ether. After stirring for 30 minutes at 0° C , 9.0 g. (0.033 mole) of solid mercuric chloride is added in portions, keeping the temperature near 0° C . 60 In about one hour the mercuric chloride dissolves. Stirring is continued one-half hour longer. At this point formation of the 2,3-dichloro-3,4,4-trifluoro-1-cyclobutenylmercuric chloride is essentially complete. It can either be isolated or transformed in situ to the desired diorganomercury derivative. Isolation is carried out as follows.

Water is added to the completed reaction mixture and the precipitated solids filtered off and washed with a large volume of ether. The filtrate is washed with 20 ml. of cold water, dried over anhydrous magnesium sulfate 65 and evaporated to dryness. The 2,3-dichloro-3,4,4-tri-

fluoro-1-cyclobutenylmercuric chloride is isolated as a white solid.

(B) Preparation of 2,3-dichloro-3,4,4-trifluoro-1-cyclobutenylmethylmercury.

To the in situ prepared 2,3-dichloro-3,4,4-trifluoro-1-cyclobutenylmercuric chloride is added dropwise an ethereal solution containing 0.033 mole of methylolithium while keeping the temperature about 0° C. After the addition, stirring is continued one to two hours longer. The reaction is then allowed to come to room temperature, water added and the ethereal solution of 2,3-dichloro-3,4,4-trifluoro-1-cyclobutenylmethylmercury dried over anhydrous magnesium sulfate. The product is purified by distillation.

Using the procedure of Example 1 the following compounds are prepared.

Example 2

5

10

15

20

From the appropriate chloromercuri derivative of 1-bromo-2,3-dichloro-3,4,4-trifluoro-1-cyclobutene and trifluorovinyllithium.

Example 3

25 and

25

From the appropriate chloromercuri derivative of 1-bromo-2,3-dichloro-3,4,4-trifluoro-1-cyclobutene and pentafluorophenyllithium.

Example 4

35

From the appropriate chloromercuri derivative of 1-bromo-2-chloro-3,3,4,4,5,5-hexafluoro-1-cyclopentene and methylolithium.

Example 5

45 R₁ is selected from the group consisting of —CH₃, —CF=CF₂,

From the appropriate chloromercuri derivative of 1-bromo-2-chloro-3,3,4,4,5,5-hexafluoro-1-cyclopentene and trifluorovinyllithium.

Example 6

50

and

55

From the appropriate chloromercuri derivative of 1-bromo-2-chloro-3,3,4,4,5,5-hexafluoro-1-cyclopentene and pentafluorophenyllithium.

Example 7

60

From the appropriate chloromercuri derivative of 1-bromo-2-chloro-3,3,4,4-tetrafluoro-1-cyclobutene and methylolithium.

Example 8

70

From the appropriate chloromercuri derivative of 1-bromo-2-chloro-3,3,4,4-tetrafluoro-1-cyclobutene and trifluorovinyllithium.

75

Example 9

From the appropriate chloromercuri derivative of 1-bromo-2-chloro-3,3,4,4-tetrafluoro-1-cyclobutene and pentafluorophenyllithium.

As will be apparent to those skilled in the art, numerous modifications and variations of the formulation of the gyro flotation fluids illustrated above may be made without departing from the spirit of this invention or the scope of the following claims.

We claim:

1. A fluorinated organomercury compound selected from the class consisting of

30 wherein R is selected from the group consisting of —CH₃, —CF=CF₂,

45 R₁ is selected from the group consisting of —CH₃, —CF=CF₂,

50 R₂ is selected from the group consisting of —CH₃, —CF=CF₂, and

55 and X is selected from the group consisting of chlorine, bromine, fluorine and —HgCH₃.

2. A fluorinated organomercury compound of claim 1 wherein the compound is

60 3. A fluorinated organomercury compound of claim 1 wherein the compound is

4. A fluorinated organomercury compound of claim 1 wherein the compound is

5. A fluorinated organomercury compound of claim 1 wherein the compound is

6. A fluorinated organomercury compound of claim 1 wherein the compound is

7. A fluorinated organomercury compound of claim 1 wherein the compound is

8. A fluorinated organomercury compound of claim 1 wherein the compound is

9. A fluorinated organomercury compound of claim 1 wherein the compound is

10. A fluorinated organomercury compound of claim 1 wherein the compound is
